UNITED STATES PATENT OFFICE

ANTHONY COVIELLO, OF DENVER, COLORADO

DESIGN FOR A SIGNAL-LIGHT CASING

Application filed July 8, 1929. Serial No. 31,969. Term of patent 14 years.

To all whom it may concern:

Be it known that I, ANTHONY COVIELLO, citizen of the United States, residing at the city and county of Denver and State of Colorado, have invented a new, original, and ornamental Design for Signal-Light Casings, of which the following is a specification, reference being had to the accompanying drawing, forming part thereof.

Fig. 1 is a front elevation of my improved signal light casing.

Fig. 2 is an end elevation, and

Fig. 3 is a rear elevation thereof.

I claim:

The ornamental design for a signal light casing, as shown.

In testimony whereof I affix my signature.
ANTHONY COVIELLO.
